MACHINE FOR CENTRIFUGAL CASTING

William D. Sargent, New York, N. Y., and William A. Geisler, Newark, N. J., assignors, by mesne assignments, to Durafer (Inc.), Dover, Del., a corporation of Delaware

Application August 6, 1931, Serial No. 555,464

12 Claims. (Cl. 22—65)

The present invention relates to molding machines and methods of casting articles centrifugally, and embodies, more specifically, an improved molding machine wherein the centrifugal molding operations are greatly simplified to enable a maximum rate of production to be maintained, together with a maximum efficiency of each molding operation.

More particularly, the invention embodies an improved molding machine and method of casting, centrifugally, liners for brake drums, although the invention is applicable to the manufacture of many articles wherein the properties of centrifugally cast metal are desired and the character of the articles such as to adapt them to be cast centrifugally. Brake drum liners may either be formed with a slight draft, of uniform thickness, or with suitable non-cylindrical surfaces upon the outer peripheries to facilitate the securing of the liners to brake drum shells in the manufacture and assembly of the brake drums.

It is contemplated, by the present invention, to provide an improved molding machine for casting these liners centrifugally at a rapid rate, the machine being of such character as to enable the mold to be quickly and easily stripped from the casting, the pouring and associated operations in connection with the casting of liners being effected in a correspondingly easy manner.

More particularly, the invention is embodied in a centrifugal mold which is capable of being supported upon a horizontal plane and actuated mechanically by the operator.

An object of the invention, accordingly, is to provide an improved mold for casting articles centrifugally, wherein the article may be effectively removed from the mold.

A further object of the invention is to provide a mold of the above character wherein the mold may be effectively stripped from the casting, the latter being readily removed from the table upon which it is cast.

A further object of the invention is to provide a molding machine for molding elements which are separable in a horizontal plane to effect the stripping of the mold from the casting.

A further object of the invention is to provide an improved horizontal mold for centrifugal casting, wherein the means for rotating the mold is effectively ventilated to prevent overheating thereof during operation of the mold.

A further object of the invention is to provide an improved mold for centrifugally casting articles, the mold being formed by centrifugal casting.

A further object of the invention is to provide a centrifugal mold which is simple in construction, light in weight, and adapted to be readily operated manually to enable molding operations to be effected rapidly and the castings removed from the mold by stripping the latter therefrom.

A further object of the invention is to provide an improved method of casting articles centrifugally, wherein the casting is effected in a horizontal plane and the mold is stripped from the casting, leaving the casting resting upon the horizontal table.

Further objects of the invention, not specifically enumerated above, will be apparent in connection with the following description, in which reference is made to the drawings, wherein:

Figure 1 is a view in section, taken through the axis of a molding machine constructed in accordance with the present invention, as indicated by line 1—1 of Figure 2, and looking in the direction of the arrows.

Figure 2 is a plan view of a molding machine constructed in accordance with the present invention.

Figure 3 is a view similar to Figure 1, showing the modified form of mold constructed in accordance with the present invention.

Referring to Figures 1 and 2, a mold foundation is illustrated at 10, and may be provided with a recess 11, in which an electric motor, or other suitable mold rotating means, 12 is provided.

The mold consists of a horizontal table 13, which is formed with a concave upper surface 14 to form a pouring plate. This pouring plate causes the metal to climb upwardly and be directed into the mold to fill the same almost instantaneously. The table is connected at 16 to the motor shaft 17, and is thus adapted to be driven directly from the motor. It will be seen that the foregoing construction affords a space between the table and the motor, whereby ventilation of the latter may be effected. This is important in view of the fact that, during operation of the machine, the table becomes heated and unless suitable provision were made for cooling the motor, dangerous overheating thereof would result.

In the form of machine shown in Figure 1, the mold is of such character as to form a circumferential rib upon the outer surface of the article, such outer surface tapering up to the base of the rib. In order that this article, after being molded, may be effectively removed from the mold, the latter is made in two sections, viz, lower section 18, and upper section 19. The lower section 18

is bolted to a mounting ring 20 by means of bolts 20', and the extremity thereof is suitably tapered to form the desired profile on the extremity of the article.

5 The upper section 19 is formed with a flange 21 and a recessed portion 22, which is adapted to engage the upper surface of the lower portion 18 to provide a fluid tight fit. A longitudinally disposed groove 23 is formed in the upper section, 10 and a peripheral flange 24 is provided to define the thickness of the article to be molded. Suitable handles 25 may be provided to facilitate the removal of the upper section 19 of the mold from the cooperating section, and keepers 26 are provided to secure the upper section in the position 15 shown in Figure 1. Springs 27 may be provided to urge the keepers yielding into the position shown in Figure 1, and cam faces 28 may be formed on the keepers to enable the upper section 19 to be automatically latched in molding position upon the positioning of the upper section upon the lower section 18.

In order that the upper section may be stripped effectively from the casting, a plurality of axially movable lifter rods 29 are slidably mounted in bushings 18' formed on the lower section 18. Each rod 29 is connected to a carrier 31 which is disposed below the table 13.

The carrier 31 and the rods 29 are elevated by 30 means of a lever 32, which is provided with a forked extremity 33, having rollers 30 to engage the carrier 31 at a plurality of positions. The lever 32 is pivoted on the foundation 10 by means of a bracket 34, and spring 35 normally urges the forked extremity 33 downward with the carrier 31. A treadle 36 is mounted on the lever 32, and thus facilitates the manual operation of the mold. Brackets 40 are carried on the motor and pivot arms 41 thereon intermediate the ends thereof. 40 Rollers 42 and 43 are journaled on the ends of the arms 41 to engage the rings 20 and 31, respectively. Ring 20 is formed with an outer track 44 and ring 31 is formed with an inner track 45, the respective rollers 42 and 43 engaging these 45 tracks to facilitate the operation of the machine. Thus when the annular member 31 is raised by operation of the treadle 36, the diametrically oppositely disposed levers 41 are rotated by reason of the engagement of rollers 43 with the web 45 50 of the annular member 31, and as a result thereof roller 42 on the other extremity of levers 41 engage the web 44 of annular member 20 and cause the same to lower.

In the construction shown in Figure 3, a horizontal table 50 receives a mold 37 which is adapted to form an article with a uniform exterior surface. This mold 37 is elevated by means of lifters 38, which are secured to a carrier 39, in a fashion similar to the corresponding elements 60 in the construction shown in Figure 1. The means for elevating the mold may be similar to the corresponding means described in connection with the construction shown in Figure 1, only so much of such construction being utilized as is necessary to elevate the mold. It has been found that the serviceability of the construction described above is materially improved by forming the mold by centrifugal casting operations. The invention, 70 therefore, further contemplates the construction of the mold sections, above referred to, by centrifugal casting operations, the metal used therein being of a special heat resistant alloy to impart the desired characteristics to the mold. For 75 example, nickel and chromium form a suitable

alloy, it being available in one form under the name "nickchrome".

From the foregoing description, it will be seen that a mold has been provided wherein the casting is readily formed and removed by stripping the molding therefrom. Thus the stripping operation takes place quickly, and the operation of the machine, therefore, is such as to effect a substantially continuous molding operation. The elements of the mold are such as to enable the driving mechanism to be effectively cooled, and the provision of a centrifugally cast mold materially improves the operation thereof.

To render the casting operations more efficient and effect a substantially continuous operation with the machine, a heat balance is maintained between the mold, pouring plate and casting. It has been found that the foregoing results are obtained by providing substantially six times the volume of metal in the mold as that of the casting, and where the size of the castings is substantially the same in surface area, this proportion of cross-sectional area between the mold and casting gives excellent results. This proportion must be greater than one but may vary, within 25 limits, depending upon the apparatus and conditions attending different operations.

To determine the thickness of the casting, and hence the volume of metal therein, the lip or flange 24 is formed on the mold, the depth of 30 the lip being a measure of the volume of the metal in the casting.

While the invention has been described with specific reference to the constructions shown in the accompanying drawings, it is not to be limited 35 save as defined in the appended claims.

What we claim is:

1. A machine for casting centrifugally comprising a horizontal table, means to rotate the table, a mold on the table, means carried by the 40 table to elevate the mold from the table, and stationary means to actuate the elevating means.

2. A machine for casting centrifugally comprising a horizontal table, means to rotate the table, a mold on the table, means carried by the 45 table to elevate the mold from the table, means on the table to secure the mold thereto, and stationary means to actuate the elevating means.

3. A machine for casting centrifugally comprising a horizontal table, means to rotate the 50 table, a mold carried by the table, elevating means for said mold extending below the table, means to secure the mold to the table, and stationary means for engaging said elevating means to elevate said mold.

4. A machine for casting centrifugally comprising a rotatable pouring plate, a plurality of mold sections associated therewith, means to elevate one of the sections from the plate, and means to depress another of the sections below 60 the plate.

5. A machine for casting centrifugally comprising a rotatable pouring plate, a plurality of mold sections associated therewith, means to simultaneously elevate one of the sections from the plate and to depress another of the sections below 65 the plate.

6. A machine for casting centrifugally comprising a rotatable pouring plate, a plurality of mold sections associated therewith, means to elevate one of the sections from the plate, and means actuated by the last named means to depress another of the sections below the plate.

7. A machine for casting centrifugally comprising a rotatable pouring plate, a plurality of 75

mold sections coaxial with the plate and rotatable therewith, means to move the sections axially in opposite directions, and means to actuate the sections simultaneously.

- 5 8. A machine for casting centrifugally comprising a rotatable pouring plate, an outwardly flaring lip on the plate, a lower mold section having an inwardly flaring lip to engage the lip on the plate and form a substantially fluid tight joint therewith, an upper mold section seated on the lower section, cooperating surfaces between the sections to form a substantially fluid tight joint therebetween, means to elevate the upper section, and means to depress the lower section.
- 10 9. A machine for casting centrifugally comprising a rotatable pouring plate, an outwardly flaring lip on the plate, a lower mold section having an inwardly flaring lip to engage the lip on the plate and form a substantially fluid tight joint therewith, an upper mold section seated on the lower section, cooperating surfaces between the sections to form a substantially fluid tight joint therebetween, means to elevate the upper section, means to depress the lower section, and means to actuate the last named means.
- 15 10. A machine for casting centrifugally comprising a rotatable pouring plate, an outwardly flaring lip on the plate, a lower mold section having an inwardly flaring lip to engage the lip on the plate and form a substantially fluid tight joint therewith, an upper mold section seated on the lower section, cooperating surfaces between the sections to form a substantially fluid tight joint therebetween, means to move the

upper section, means to move the lower section, means between the last named means to cause axial movements of the last named means in opposite directions, and means to actuate the moving means.

11. A machine for casting centrifugally about a vertical axis comprising a lower horizontal mold member, an upper horizontal mold member engageable therewith, bushings spaced around the outer edge of said lower mold member, vertical extending rods slidably arranged in said bushing and fixed to a radial flange on the lower edge of the upper mold member, an annular horizontal flanged ring secured to the lower ends of said rods and stationary means having rollers engaging said flanged ring adapted to lift said upper mold member.

12. A machine for casting centrifugally about a vertical axis comprising a lower horizontal mold member, an upper horizontal mold member engageable therewith, bushings spaced around the outer edge of said lower mold member, vertical extending rods slidably arranged in said bushing and fixed to a radial flange on the lower edge of the upper mold member, an annular horizontal flanged ring secured to the lower ends of said rods, stationary means having rollers engaging said flanged ring adapted to lift said upper mold member, and spring pressed latches pivotally secured to said lower member and adapted to engage the flange on said upper member.
